SAFETY GAS-BURNER

Hans Arquint, Sursee, Switzerland

Application June 12, 1935, Serial No. 26,284
In Germany June 15, 1934

5 Claims. (Cl. 158—117.1)

The present invention relates to improvements in a safety cut-off device for gas burners of the kind where the admission of gas to the burner is cut off if the pilot flame should be extinguished.

5 An object of this invention is to provide a gas flow control device comprising a manually actuated stop cock and a thermostatically actuated poppet valve for separately controlling the flow of gas to a burner in which the stem of the 10 poppet valve is slidably mounted in the plug or body of the stop cock.

Another object of this invention is to provide 15 a gas flow control device comprising a manually actuated stop cock and a thermostatically actuated poppet valve for separately controlling the flow of gas to a burner in which the stem of the poppet valve is slidably mounted in the plug or body of the stop cock and said poppet valve is urged to a closed position by a spring and adapted 20 to be opened by the thermostat.

With these and other important objects in view, which may be incident to my improvements, the invention resides in the parts and combinations to be hereinafter set forth and claimed, with 25 the understanding that the several necessary elements comprising my invention may be varied in construction, proportions and arrangement, without departing from the spirit and scope of the appended claims.

30 In order to make the invention more clearly understood, there is shown in the accompanying drawings means for carrying the same into practical effect without limiting the improvements in their useful applications to the particular constructions which, for the purposes of explanation, have been made the subject of illustration.

In the drawings:

Figure 1 is a vertical longitudinal sectional view of a gas burner control constructed according to one form of the invention;

Fig. 2 is a similar view of a portion of a modified form;

Fig. 3 is an end view of the structure shown in Fig. 1;

Fig. 4 is a detail view of limit guide;

Figs. 5 and 6 are detail views of a lever of the thermostat; and

Fig. 7 is a vertical longitudinal sectional view of another modified form of the invention.

50 Referring to the drawings, the general arrangement of the control device comprises a valve chest or casing 1 provided with a main gas nozzle 2 feeding the burner, a gas inlet 6, a seat for the manually-actuated rotatable gas cock plug 4, 55 a chamber 5 enclosing the transmission lever 34

and closed by a cap 36, and bosses 3 and 3' supporting the thermostat rod 24'. Besides, there is a passageway 8 for the flow of the pilot gas supply from the gas inlet 6 to the seat of plug 4 and a passageway 16 from this seat to a chamber 17 formed in boss 3' and closed by a screw cap 18.

The rotatable plug or body 4 of the manually actuated gas cock is of hollow construction and is provided with a central axially extending tubular boss 4' in which is axially slidably mounted the hollow tubular stem of the thermostatically actuated main valve 10. This valve is of the poppet type and is resiliently urged against its seat 10' by a coil spring 9. The plug 4 is provided with a port 4" adapted to register with the gas inlet 6. When the plug 4 is in the position shown in Fig. 1 with the port 4" registering with inlet 6, gas will flow from the inlet 6 through port 4" into the annular chamber in the plug 4 around 20 the head of valve 10 (when in open position) through the opening surrounded by valve seat 10' and into chamber 5. From chamber 5, the gas flows through nozzle 2 into the burner.

A pin 13 is carried by plug 4 and engages in 25 an axially extending slot 12 of the tubular stem of valve 10. This construction causes valve 10 to rotate with plug 4 to effect a grinding action between valve 10 and its seat, thereby insuring a tight fit and yet permit axial displacement of 30 said valve within plug 4. An adjustable contact screw 11 is threaded into a split extension 7 of the valve 10 and is retained in adjusted positions by frictional engagement with the split extension.

The gas cock is retained on its seat against the pressure of spring 9 by a flat spring 28. A stop pin 30, carried by plug 4 and movable through an arcuate cut-away portion 30' of casing 1, limits the rotary movement of the cock to about 40 135°. An intermediate position is indicated by a spring catch 29 (Fig. 4) which engages pin 30. In this intermediate position, the port 4" of the cock is out of register with inlet 6, so that the gas supply to the burner is cut off completely. 45 The pilot gas supply through passageway 8 is still left open. In this position, the pilot flames 26 and 27 will burn. By further turning the plug over said spring catch 29 into its extreme closed position, the pilot gas supply will also be cut off. 50

The pilot gas supply flows through passageway 8 into the circumferential groove 14 surrounding plug 4. A longitudinal peripheral groove 15 communicates with groove 8 and passageway 16 formed in the upper portion of casing 1. The 55

groove 15 extends through an arc sufficient to provide communication between groove 8 and passageway 16 during all movement of plug 4 from full open to slightly beyond full closed positions. This enables the gas supply to the pilot light to remain open, even after the plug 4 has been moved to a closed position, as indicated by engagement of pin 30 with spring-catch 29. Upon further movement of plug 4 in the closing direction, the groove 15 will be shifted out of register with passageway 16 and the flow of gas to the latter will be stopped. This position is determined by engagement of pin 30 with one end of the recess 30'.

15 The thermostat comprises an inner member made of invar steel having a very small coefficient of expansion. This inner member, according to Fig. 1, comprises a rod 24 secured to the head of the expanding outer tubular member 25 of the 20 thermostat and an attached tubular member 24' extended into the chamber 17, where it is provided with a calibrated inlet nozzle 19 for the flow of gas to the pilot. Tubular member 24' is also provided with an outlet opening 23 communicating with the annular space between inner and outer members 24 and 25, respectively, of the thermostat. The outer member 25 has holes 26 in its underside for the heating flames, while a hole 27 in the front wall of said annular space 30 feeds the pilot flame for lighting the burner.

The tubular member 24' extending into chamber 17 is threadedly connected to a carrier sleeve 21 carrying a split clamping ring 20 which frictionally engages a controlling sleeve 22. 35 The frictional engagement between ring 20 and the sleeve 22 is sufficient to cause the sleeve 22 to move with ring 20 and the tube 24' through the limited stroke afforded within chamber 17. In this connection, it will be noted that the portion of sleeve 22 within chamber 17 is nearly as long as the distance between the end of chamber 17 closed by cap 18 and the opposite end thereof. This limits the stroke of sleeve 22 within chamber 17 to a distance sufficient to effect full opening and closing of valve 10. The frictional engagement between sleeve 22 and ring 20 enables the ring 20 and the tubular member 24' to further move after sleeve 22 has reached its limit of movement.

50 An opening 22' is provided in the outer end of sleeve 22 to permit the flow of gas from passageway 16 into chamber 17, even when sleeve 22 is against cap 18. From chamber 17, the gas flows through a calibrated nozzle 19 through tube 24' and port 23 into the interior of tube 25 and thence out through openings 26 and 27. Access to nozzle 19 for replacement is obtained by removal of cap 18.

Sleeve 22 is provided with a projecting portion 60 which extends through the inner end of chamber 17 into the chamber 5. A lever 34 mounted on fulcrum pivot 33 in chamber 5 has its upper short arm forked to freely embrace tube 24' and provided with lugs 32 to engage the projection of sleeve 22. The lower long arm of lever 34 engages the contact screw 11.

In Fig. 1, the lever 34 is in the position which it assumes when the tube 25 is cold, due to the absence of flames from openings 26. After the 70 gas flowing from these openings is ignited, the tube 25 is heated and expands, causing the tube 24', ring 20 and sleeve 22 to shift to the left (Fig. 1). Displacement of sleeve 22 rocks lever 34 to open valve 10 against the action of spring 9. 75 Opening of valve 10 places the interior of plug 4

in communication with chamber 5 and when the port 4" is in register with inlet 6, gas will flow into chamber 5 and out through nozzle 2 to the burner.

If, for any reason, the burning gas flowing 5 through openings 26 should be extinguished, the tube 25 would cool down and contract. This would cause the sleeve 22 to shift to the right (Fig. 1) and permit valve 10 to close, shutting off the flow of gas through chamber 5 and nozzle 10 2 to the burner.

As shown in Fig. 2, the construction may be modified by positioning a sleeve 22a directly on tube 24' for transmitting the movement of the tube to the lever 34.

Figs. 5 and 6 illustrate how the leverage ratio of lever 34 may be varied within large limits by displacing the lugs 32 on the shorter arm of lever 34.

In Fig. 7, a modified form of the device of Figs. 20 1-6 is shown.

The apparatus of Fig. 7 comprises a valve chest or casing 51 provided with a main gas nozzle 2a feeding the burner, a gas inlet 59, a seat for the manually-actuated rotatable gas 25 cock plug or body 4a, a chamber 5a enclosing the transmission lever 34a and closed by a cap 36a and means for supporting a thermostat.

Rotatable cock plug 4a, which is held on its seat by spring 28', is of hollow construction and 30 is provided with a port 4d adapted to register with gas inlet 59 for the admission of gas into the space 4e in plug 4a which opens into valve chamber 10b. An axially extending tubular boss 4c is formed within the plug 4a and slidably receives the tubular stem 10c of poppet valve 10a. A spring 9a urges valve 10a onto a valve seat 10d to close communication between chambers 10b and 5a. Valve 10a is caused to rotate with plug 4a by means of a pin 60' carried by valve stem 40 10c and slidably positioned in the axially extending slot formed in boss 4c. By reason of this construction, valve 10a is rotated on its seat when plug 4a is turned and insures a tight fit between valve 10a and its seat.

Valve 10a is shifted from its seat by means of a plunger 53 extending through valve stem 10c. Plunger 53 is provided with an enlarged head 55 adapted to engage valve 10a and has an adjusting contact screw 54 extending axially there-through for engaging the lower end of lever 34a. The head 55 of plunger 53 is flattened on its sides and is received between lugs 56 carried by lever 34a to prevent rotation of plunger 53. It will be realized that by adjusting screw 54, the opening of valve 10a relative to the position of lever 34a may be varied.

The bore within boss 4c extends completely through plug 4a and is enlarged at its outer end to form a compartment 4g in which is mounted 60 a valve body 50 carried on the end of plunger 54. This valve 50 serves to close communication between the compartment 4f in boss 4c and compartment 4g by seating on the shoulder formed between these two compartments. Valve 50 is urged onto its seat by a coil spring 51 which engages cap 4b closing compartment 4g. The lever 34a opens valve 50 by displacing plunger 53, and in this connection it will be noted that the head 55 is so positioned relative to valve 10a that valve 50 is opened prior to valve 10a.

Gas for the pilot light flows from inlet 59 through passageway 58 into recess 52' formed on the periphery of plug 4a and thence through duct 52 in plug 4a into compartment 4f. When 75

- valve 50 is open, the gas flows from compartment 4f into compartment 4g and through duct 49 into recess 47 formed on the periphery of plug 4a. Recess 47 is adapted to register with duct 45a which communicates with chamber 45'. A duct 45 allows the gas to flow from chamber 45' into chamber 44a. From the latter chamber, the gas flows to the pilot nozzle 37, as will be described hereinafter.
- 10 As described hereinbefore, the flattened head 55 of plunger 53 prevents this plunger and valve 50 carried thereby from rotating. Thus, when plug 4a is rotated, a grinding action between valve 50 and its seat will take place.
- 15 The thermostat comprises a holding tubular casing 39 secured to the boss 3a of the casing 57 by a union nut 3b. The attaching end of tube 39 is flanged and carries a flanged bushing 39' which bears against the end of and partially enters boss 3a. The outer end of tube 39 carries a bushing 39a and cooperates with bushing 39' to support the expansible tube 38. The outer end of tube 38 is anchored to bushing 39a and the inner end is slidably supported by bushing 39'.
- 20 A tubular fitting 40 is secured to the inner end of tube 38 to slide therewith. Friction ring 41 surrounds the fitting 40 and is held thereon by screw 41'. Ring 41 is constructed to fit within sleeve 42 with sufficient friction to cause sleeve 42 to axially move with fitting 40. Sleeve 42 is axially slidably mounted within boss 3a for limited movement and when said sleeve has reached its limit of movement, the frictional engagement 25 between the same and ring 41 will enable the ring 41 and the structure carrying it to move further without damage.
- 25 Sleeve 42 has a tubular extension of reduced diameter which is slidably mounted in chamber 44a. Lever 34a has its upper forked end mounted to pivot about fulcrum 33a and embraces the extension 43. Sleeve 42 engages lugs 32a on lever 34a for imparting movement of the thermostat thereto to open valves 10a and 50.
- 30 Tube 38, fitting 40, screw 41' and sleeve 42, 43 have a passage therethrough for the flow of gas from chamber 44' to nozzle 37. The flow of gas through this passage is calibrated by nozzle 44, which may be replaced by removing cap 18'.
- 35 In addition to the path of flow of gas from inlet 59 through passageway 58, recess 52', duct 52, chambers 4f, 4g, duct 49, recess 47, duct 45a to chamber 45', etc., to the pilot light nozzle, there is provided an auxiliary flow path. For 40 this purpose, plug 4a is provided with a circumferential groove 14' communicating with recess 52'. Groove 14' registers with duct 46c which communicates with socket 46a. A valve guide 46b is fitted into socket 46a and has a valve stem 46 extending axially therethrough. A small chamber 46d is provided in the inner end of guide 46b, which is connected by duct 46e with socket 46a. The chamber 46d is closed by a valve on the end of stem 46 normally held in a closed position 45 by spring 46f. It will be realized that by pushing on knob 48 to open valve 46, gas will flow from socket 46a through duct 46e into chamber 46d into chamber 45' and thence to pilot nozzle 37 as hereinbefore described.
- 45 At this point it should be noted that recesses 47 and 52' extend circumferentially of the plug 4a through a distance sufficiently great to register with ducts 45a and 58, respectively, from a full open position of plug 4a (port 4d in register 50 with inlet 59) to slightly beyond a closed posi-
- tion. This allows the pilot light to remain lit after the flow of gas to burner B has been manually shut off.
- 5 When the thermostat is cold, both valves 10a and 50 will be closed, and since gas cannot flow through duct 52 etc., to the pilot, it is necessary to push knob 48 to open the auxiliary flow path from inlet 59 by way of valve 46 to the pilot. The pilot may then be lit while holding knob 48 in and the knob 48 is held in until the thermostat 10 is heated sufficiently to open valve 50. Then the knob 48 may be released and the pilot will burn with gas supplied through the regular channel. After the thermostat has been further heated, the valve 10a will be opened to permit the flow of 15 gas to the burner. Then, the flow to the burner may be manually controlled by the plug 4a.
- 20 To facilitate lighting of the pilot, a tube 91 connected to chamber 45' and extending under tube 38 may be provided. Tube 91 is provided with a series of openings in its upper surface so that when one of the openings remote from the pilot is lighted, the flame will travel to the end of tube 91 and ignite the pilot flame. This tube 91 also serves to heat thermostat tube 38 and 25 for this purpose the underside of tube 38 is cut away. Also, an opening 37' is provided in the underside of tube 38 at the nozzle 37 for ignition of the pilot light.
- 30 When the pilot is extinguished, the thermostat will cool off and valves 10a and 50 will successively be closed to shut off the flow of gas to the burner and the pilot and gas can be fed to the pilot only by pressing knob 48 as explained hereinbefore.
- 35 While I have shown and described the preferred embodiment of my invention, I wish it to be understood that I do not confine myself to the precise details herein set forth by way of illustration as it is apparent that many changes and 40 variations may be made therein by those skilled in the art, without departing from the spirit of the invention or exceeding the scope of the appended claims.
- 40 I claim:—
- 45 1. A safety control device for gas burners, comprising a valve chest having a gas inlet and divided into a valve chamber and a thermostat-lever chamber, said valve chamber communicating with said gas inlet and said lever chamber, a gas outlet 50 nozzle for the flow of gas from said lever chamber to a gas burner, a manually-actuated plug valve in said valve chamber and provided with communicating radial and axially extending ports for the flow of gas into said valve chamber 55 when the radial port is in register with the gas inlet, a poppet valve for closing communication between the valve chamber and said lever chamber, said poppet valve having a stem axially slidably mounted with said plug, resilient means urging said poppet valve to a closed position, a thermostat having a pilot light associated therewith, said valve chest having passageways therein for supplying gas from said inlet to said pilot light, said plug valve having passageways co- 60 operating with those in the valve chest to control the flow of gas to the pilot, a lever pivotally mounted in said lever chamber, means carried by said thermostat for actuating said lever, and adjustable contact means carried by said poppet 65 valve for engaging one end of said lever to transmit displacement of said lever to said valve to open the same.
- 70 2. A safety cut-off device for gas burners, comprising a valve chest having an inlet for the 75

- admission of gas and a closed chamber for a transmission lever, a main gas nozzle for feeding gas to a burner, a rotatable gas cock between said chamber and the gas inlet, said gas cock having a main passageway and passageways for the pilot gas, a main gas valve in the main passageway of the cock having a hollow stem slidably held in an axial bore of the cock, an adjustable contact screw carried by said main valve and projecting into the chamber of the valve chest, a helical spring urging the main valve to a closed position, a thermostat comprising a tubular expanding member and a movable member formed as a conduit for the flow of pilot gas and ending in a chamber communicating with the passageways of the gas cock, a calibrated nozzle fitted into said end of the movable member of the thermostat, and a transmission lever arranged in said chamber of the valve chest and being in operative contact with the movable member of the thermostat and the adjustable screw of the main valve.
3. A safety cut-off device according to claim 2, in which the valve stem is slotted and in which the cock is provided with a carrier pin engaging in the slot of the valve stem for rotating said stem and grinding the valve on its seat at each turning movement of the cock.
4. A safety control device for gas burners, comprising a valve chest having a gas inlet and divided into a valve chamber and a thermostatic lever chamber, said valve chamber communicating with said gas inlet and said lever chamber, a gas outlet nozzle for the flow of gas from said lever chamber to a gas burner, a manually-actuated plug valve in said valve chamber and provided with communicating radial and axially extending ports for the flow of gas into said valve chamber when the radial port is in register with the gas inlet, said plug having an axially extend-
- ing tubular boss and an enlarged bore communicating with the interior of said boss, a poppet valve for closing communication between said valve and lever chambers, said poppet valve having a tubular stem slidably mounted within the bore of said boss, a spring urging said poppet valve to a closed position, a plunger extending through said tubular valve stem having a head on one end and a pilot control valve on the other end within the enlarged bore of said plug for shutting said large bore from the bore in said tubular boss, a spring urging said pilot control valve to a closed position, a tubular thermostat having a pilot light nozzle therein adjacent one end thereof, means for mounting said thermostat on said valve chest with said pilot light positioned adjacent the burner, said thermostat having a tubular movable member extending through said lever chamber into a pilot feed chamber provided in said chest, said chest having passages connecting said pilot feed chamber and said inlet with said valve chamber, said plug having passages therein connected to the bore in said boss and the enlarged bore respectively and adapted to register with the passages in the chest to conduct gas from the inlet to the pilot feed chamber, and a pivoted lever in said lever chamber having one end contacting with said plunger and the other end actuated by the movable member of the thermostat to open said poppet and pilot valves against the action of their springs.
5. A device according to claim 4, in which the chest and plug are provided with communicating passageways forming an auxiliary path of flow for gas from said inlet to said pilot feed chamber, and a spring-closed manually-opened valve in said auxiliary flow path for admitting gas to said pilot when said thermostatically actuated pilot control valve is closed.

HANS ARQUINT. 40
